UNITED STATES PATENT OFFICE

92,353

DESIGN FOR A HEADLIGHT FOR AUTOMOBILES OR THE LIKE

Martin R. Hoag, Chicago, Ill.

Application November 1, 1933, Serial No. 49,627

Term of patent 3½ years

To all whom it may concern:

Be it known that I, MARTIN R. HOAG, a citizen of the United States, residing at Chicago, in the county of Cook, and State of Illinois, have invented a new, original, and ornamental Design for a Headlight for Automobiles or the like, of which the following is a specification, reference being had to the accompanying drawing forming a part thereof:

In the drawing,

The figure is a perspective view of a headlight for automobiles, showing my new design.

I claim:

The ornamental design for a headlight for automobiles or the like as shown.

MARTIN R. HOAG.
